UNITED STATES PATENT OFFICE.

ARTHUR JAQUES, OF REDDING, POLMONT STATION, SCOTLAND, AND GORDON WELLS,
OF ST. ALBANS, ENGLAND, ASSIGNEES TO NOBEL'S EXPLOSIVES COMPANY, LTD.,
OF GLASGOW, SCOTLAND.

EXPLOSIVE PRIMING COMPOSITION.

1,106,147.

Specification of Letters Patent. Patented Aug. 4, 1914.

1 Drawing.

Application filed October 4, 1913. Serial No. 793,437.

To all whom it may concern:

Be it known that we, ARTHUR JAQUES and GORDON WELLS, subjects of the King of Great Britain, residing at Redding, Polmont Station, Scotland, and St. Albans, Herts, England, respectively, have invented certain new and useful Improvements in the Manufacture of Explosive Priming Compositions, of which the following is a specification.

In the manufacture of electric fuses and electric detonators two methods are in use to enable the priming composition to be fired by an electric current, such fuses being known as high-tension and low-tension respectively. In the case of high-tension fuses the priming composition is such that the substance is itself made a conductor of the electric current by the addition of a suitable material, and the priming composition fires when the current, reaching a certain strength, raises its temperature or that of some particles in it to a point at which ignition commences and propagates throughout the mass. In the case of low-tension fuses ignition is obtained by embedding in the priming composition a fine wire of platinum or other material which becomes heated by the passage of the electric current. In this case also when the temperature of the wire reaches a certain value ignition commences in the particles at the surface of the wire and spreads throughout the mass. When these fuses are made up into electric detonators for detonating explosives as in mines, and quarries, it is frequently necessary to fire a number of shots simultaneously, and for this purpose more especially in the case of low-tension electric detonators or electric fuses, it is customary to connect a number of these in series and by means of an exploder to pass sufficient current to fire the whole number at once.

It is found in practice that as the number of electric detonators or electric fuses connected in series increases more power is required. Two circumstances contribute to the need for this additional power, namely (1) the extra resistance of the additional fuses and (2) the fact that a larger current is found to be required to fire the larger number at once. This necessitates a disproportionate increase in the size of the exploders as the number of shots to be fired increases.

For a given type of fuse it naturally follows that the lower the temperature of ignition of the priming composition, the less current is required to cause ignition. This might be expected to hold good for the case of a number of shots in series, as well as for single shot firing and we find this to be the case.

The present invention relates to the manufacture of priming compositions of low flash-point for use in electric fuses or electric detonators or for producing mixtures for use in cases where a low flash-point is essential.

We have found that the compound known as benzoyl peroxid when mixed with certain suitable priming compositions, explosives, or explosive mixtures has the property of considerably reducing the temperature of ignition of the resulting mixture. Benzoyl peroxid when heated alone gives off oxygen with some violence at a temperature of about 112° C., and this decomposition induces the explosive reaction of certain substances with which it may be mixed to take place almost at its own temperature of decomposition.

As examples of the use of benzoyl peroxid in this manner we may quote the following results which were obtained using the ordinary flash-point apparatus, with a time-interval of 10 seconds:

Mixture No. 1.—A mixture of fulminate of mercury 60% and benzoyl peroxid 40% flashes at 112° C. Fulminate of mercury alone flashes at 180° C. or over.

Mixture No. 2.—A: cuprammonium thiosulfate ($CuS_2O_3 \cdot 4NH_3$) 43%, potassium chlorate 57%.

A mixture of (A) 60% and benzoyl peroxid 40% flashes at 115° C. Mixture A alone flashes instantaneously at 220° C. Below this temperature however, it does not flash at all.

Mixture No. 3.—A mixture of lead thiosulfate (PbS_2O_3) 1 part, potassium chlorate 1 part, and of benzoyl peroxid ($C_{14}H_{10}O_4$) 1 part flashes at 112° C. A mixture of equal parts of lead thiosulfate and potassium chlorate does not flash below 200° C.

A comparison of electric detonators containing fulminate of mercury alone as priming composition, and those containing mixture No. 1 showed that the latter required only three quarters of the current needed

to fire the former, while for a given exploder the number of electric detonators containing mixture No. 1 as priming composition that could be fired with certainty 5 was one quarter more than the number containing fulminate alone.

We declare that what we claim is:—

1. As a new article of manufacture, a mixture of benzoyl peroxid and an explosive, 10 said mixture having a lower temperature of ignition or flashing than such explosive.

2. As a new article of manufacture, a composition consisting of an ordinary priming composition, about 60% to 66%, and benzoyl 15 peroxid, 40% to 33%.

In witness whereof, we have hereunto signed our names this 18th and 2d days of September 1913, in the presence of two subscribing witnesses.

ARTHUR JAQUES.
GORDON WELLS.

Witnesses to the signature of the said Arthur Jaques:

ALEXANDER FORBES,
JAMES MITCHELL KING.

Witnesses to the signature of the said Gordon Wells:

C. LUDLOW LIVINGSTON,
WILLIAM I. DEES.
